W. A. DAVIS.
WOOL PACKING DEVICE.

No. 37,810.

Patented Mar. 3, 1863.

UNITED STATES PATENT OFFICE.

WILLIAM A. DAVIS, OF SALEM, OHIO.

IMPROVEMENT IN WOOL-PACKING DEVICES.

Specification forming part of Letters Patent No. 37,810, dated March 3, 1863.

To all whom it may concern:

Be it known that I, WILLIAM A. DAVIS, of Salem, in the county of Columbiana and State of Ohio, have invented a new and Improved Machine for Packing Wool; and I do hereby declare that the following is a full, clear, and exact description of the same, reference being had to the accompanying drawings, making a part of this specification, in which—

Figure 1 is a side sectional view of my invention, taken in the line *x x*, Fig. 2; Fig. 2, a transverse vertical section of the same, taken in the line *y y*, Fig. 1; Fig. 3, a diminished horizontal section of the same, taken in the line *z z*, Fig. 1; Fig. 4, a front view of the upper part of the same.

Similar letters of reference indicate corresponding parts in the several figures.

This invention relates to a new and improved machine for packing wool in the fleece; and it consists in the employment or use of a table provided with folding sides arranged in such a manner that they may be adjusted with the greatest facility in order to place the wool properly on the packing-strap.

The invention also consists in a novel arrangement of the cords by which the wool is bound, in order to facilitate the adjusting and tying of the same around the wool when packed; and the invention further consists in an improvement in the packing-strap, the construction of the same, and the manner in which it is applied to the working parts.

To enable those skilled in the art to fully understand and construct my invention, I will proceed to describe it.

A represents a framing, which may be constructed in any proper way to support the working parts; and *B* is a horizontal platform, which is placed in the framing, and has attached to it a box, *C*, which contains spools *a*, on which the binding-cord *b* is wound. Some distance above the platform *B* there is another platform, *D*, which is parallel with *B*. The platform *D* is provided with two side pieces, *E E*, which are attached to it by hinges *c*. To the outer side of each of these side pieces *E* there attached two bars, *F F*, which when the side pieces, *E*, are in an upright position, extend down nearly to the platform *B*, and bear against shoulders *d* near the ends of bars *G G'*, which are pivoted at their centers to the platform *B*, as shown clearly in Fig. 3.

The bars *G G'* are connected at one end by a rod, *H*, and one of said bars, *G'*, has a short rod, *I*, attached to it, said rod being also connected to a crank, *e*, on a shaft, *J*, one end of which is provided with another crank, *f*, at right angles to crank *e*. The crank *f* is connected by a rod, *g*, to a lever, *h*, which is attached to one side of the framing *A* and the rod *I* has a spiral spring, *i*, upon it, one end of which bears against the bar *G'* and the other end against a stop or bearing, *j*, on the platform *B*. (See Figs. 1 and 3.) The spiral spring *i* has a tendency to keep the ends of the bars *G G'* in contact with the lower ends of the bars *F F*, and the latter, in consequence of bearing against the shoulders *d* of the bars *G G'*, serve to prevent the side pieces, *E E*, from moving outward from a vertical position, as will be understood by referring to Figs. 2 and 3.

J' is a treadle or lever, which is placed in the lower part of the framing *A*, and has a cross-bar, *k*, attached to one end of it, said cross-bar being connected at its ends by straps *l l* to two of the bars *F F*, one of each side piece, *E*. At one end of the framing *A*, just above the platform *D*, there is a roller, *K*, the shaft *m* of which has a ratchet, *L*, at one end of it, and into this ratchet a pawl, *M*, catches the latter, being over the lever *h*, as shown in Fig. 1. The roller *K* has a groove, *n*, made longitudinally in it, and a hook, *s*, is driven centrally in the roller adjoining the groove *n*, as shown in Fig. 4.

N represents an upright plate, which is attached to the front end of the platform *D*. This plate has three upright spikes or teeth, *t t t*, in its upper edge, and at the inner side of the plate *N* there is a curved plate, *O*, which is shown in Fig. 1.

P is a strap, which may be of leather. This strap is equal in width to the platform *D*, and it has longitudinal slots *u* made in it, the slots extending nearly the whole length of the belt. One end of this strap is attached to the roller *K*, and this end has a wire or rod, *v*, fitted in it, which rod is placed in the groove *n* of the roller, the hook *s* passing through a hole in the strap and around the rod *v*. The opposite end of the strap *P* is attached to the platform *D* at the lower end of the plate *C*.

The operation is as follows: The side pieces, *E E* are, turned outward from a vertical posi-

tion, so as to be in the same horizontal plane as the platform D, and said platform with the side pieces, E E, form a table, on which the wool to be packed is placed. Previous to the placing of the wool on said table, the strap P is detached from the roller K, and the strap spread out on the platform B, so that the wool may be placed upon it. The cords b of the spools a, one also passed through holes in the platform B, and are fitted in slots in the upper ends of the spikes or teeth t. The operator then forces down the treadle or lever J', and in consequence of the latter being connected by the straps ll to a bar, F, of each side piece, E, the latter will be raised to a vertical position and all the wool thrown upon the strap P, the side pieces, E, being held in proper position by the shoulders on the bars G G', as previously described. The operator then grasps the disengaged or free end of the strap P, and draws it over the wool and connects it to the roller K, the spikes or teeth t passing through the slots in the strap. The roller K is then turned by means of a crank, Q, and the strap P wound upon the roller K, the wool being thereby compressed into a roll. When this is accomplished, the operator ties the roll by means of the cords b, and then releases the pawl M from the ratchet by pressing down the lever h. This movement of the lever h also moves the bars G G', so that the lower ends of the bars F F will be free from the shoulders d of the bars G G', and the side pieces, E E, can then be turned outward and downward to a horizontal position, the bars F coming in contact with the under surface of the platform D, and serving to hold the side pieces, E E, in a proper horizontal position. The strap P is then detached from the roller K, the compressed and bound bale or roll of

wool removed, the cords b adjusted to the spikes or teeth t, the wool placed on the platform D, the side pieces, E E, raised to a vertical position by forcing down the treadle or lever J', the strap P attached to the roller K, and the latter turned as before in order to compress the wool within it.

I would remark that the spools a may each have a spring, a*, bearing upon it to prevent them from turning casually.

Having thus described my invention, what I claim as new, and desire to secure by Letters Patent, is—

1. The hinged side pieces, E E, of the platform D, provided with the bars F and used in connection with the bars G G', or their equivalents, to serve as stops for the bars F to retain the side pieces in a vertical position, as set forth.

2. The arrangement of the bars G G', connecting rod H, spring i, rod I, crank-shaft J, and levers h J', substantially as shown, for the purpose of raising the side pieces, E E, to a vertical position and releasing the same so that they may be turned down to a horizontal position, as herein described.

3. The cords b, placed on the spools a, in connection with the spikes or teeth t, when said parts are used in connection with the slotted packing-strap P, as and for the purpose specified.

4. The packing-strap P, attached at one end to the platform D, in combination with the roller K and bearing-plate O, as and for the purpose herein set forth.

WILLIAM A. DAVIS.
